UNITED STATES PATENT OFFICE.

ALEXANDER G. McGREGOR, OF GLOBE, ARIZONA.

CAR.

1,143,641.

Specification of Letters Patent. Patented June 22, 1915.

Application filed August 10, 1914. Serial No. 856,032.

To all whom it may concern:

Be it known that I, ALEXANDER G. McGREGOR, a citizen of the United States, residing at Globe, in the county of Gila and State of Arizona, have invented or discovered certain new and useful Improvements in Cars, of which the following is a specification, reference being had therein to the accompanying drawings.

10 This invention relates to apparatus employed in metallurgical plants for the purpose of handling concentrates between the concentrator and the smelter, and more particularly to the cars in which said concentrates are transported and to certain parts of the apparatus coöperating therewith. Such concentrates are often very fine and wet and are more or less sticky, having an angle of repose which is frequently virtually 90°.

20 It is therefore inexpedient, if not practically impossible, to discharge or unload these concentrates from cars by means of chutes or the like of ordinary form, or even to dump the same from hopper bottomed cars of the usual type. As a result the usual practice for handling these concentrates consists in transporting them in open top, steel body cars having flat bottoms, or in ordinary box cars, which are emptied by shoveling out by hand,

25 thereby involving a considerable amount of manual labor which it is the primary object of the present invention to avoid.

This and other objects of the invention, together with means whereby the same may be carried into effect, will best be understood from the following description of one form or embodiment thereof illustrated in the accompanying drawings. It will be understood, however, that the particular construction described and shown has been chosen for illustrative purposes merely, and that the invention may be otherwise embodied and practised without departing from the spirit and scope thereof as defined by the

40 claims hereunto appended.

In said drawings: Figure 1 is a transverse section through the structure in which the concentrate cars are unloaded, showing one of said cars in end elevation. Fig. 2 is a side elevation of the car, partly broken away. Fig. 3 is a detail longitudinal section, on an enlarged scale, of portions of opposite ends of the car. Fig. 4 is a detail

perspective view of one of the slats constituting the car bottom. Fig. 5 is a detail perspective view of the sliding end gate which coöperates with the bottom slats. Fig. 6 is an enlarged transverse section on the line 6—6, Fig. 2. Fig. 7 is a section on the line 7—7, Fig. 3. Fig. 8 is a detail plan view broken away centrally of another form of bottom slat. Fig. 9 is a section on the line 9—9, Fig. 8.

The car constituting the main feature of the present invention comprises a frame supported by bolsters 11 upon trucks 12 of any usual or well known form, and a body, supported by said frame and having an open top or, if preferred, a closed top having suitable openings for receiving the concentrates, and a bottom from which the concentrates may be readily discharged, as will presently be explained. As herein shown the car frame comprises longitudinal side members or channel bars 13 connected by end members or channel bars 14, and intermediate longitudinal girders 15 connected with each other by one or more transverse beams or girders 16 and with the side members 13 by one or more beams or girders 17. Supported by the girders 15 and 16 are guide plates or aprons 46 and 47 for directing the flow of material discharged from the bottom of the car body as hereinafter explained.

The body of the car comprises upper vertical side walls 18 spaced from the car frame and supported therefrom by means of vertical uprights 19 and inclined braces 20, end walls 21 and 22, respectively, and a lower, hopper shaped portion comprising inclined, downwardly converging plates or walls 23 secured at their upper edges to the side walls 18, at their ends to the walls 21 and 22, and at their lower edges (as shown most clearly in Fig. 6) to upper extensions 24 of the webs of the girders 15.

The bottom of the hopper portion of the car body is composed of a series of slats 25 arranged transversely of the car and having 100 rabbed edges fitting and overlapping one another to form shiplap joints. The series of slats 25 extends continuously from the end 22, to which is secured a rabbed cross piece 27 (see Fig. 3) which fits the rabbed 105 edge of the endmost plank and makes a

- tight joint therewith, to a point a short distance from the end wall 21. The slats 25 are independently supported at their ends and are guided for movement longitudinally 5 of the car in guideways composed of angle bars 28 secured to the girders 15 and combined filler and guide plates 29 interposed between the hopper walls 23 and web extensions 24. The slats 25 are preferably formed 10 with sockets or recesses 30 adapted for engagement by a hoe or other tool for the purpose of moving said slats in their guideways 28, 29.

At the end of the series of slats adjacent 15 the end wall 21 there is provided a sliding gate 31 supported and guided upon the angle bars 28 and having a rabbeted inner edge 32 which engages and fits the rabbeted edge 26 of the endmost slat 25. The gate 31 20 when in normal position (as shown in Figs. 2 and 3) fills the space between the endmost slat 25 and the wall 21 and, by pressure against said slat, serves to hold all of the slats of the series in their normal stationary 25 position in their guides to form a continuous bottom. For the purpose of making a tight joint between the gate 31 and end wall 21 there is preferably provided a bar 33 secured by hinged bolts 34 to the car frame. 30 The gate 31 is provided with an outwardly extending screw threaded stem or shank 35 bolted or otherwise rigidly secured thereto. Said threaded stem 35 coöperates with the internally threaded opening in a sleeve 36 35 to which is keyed a hand wheel 43. The sleeve 36 is journaled in bearings 37 bolted to cross bars 38 and 39 suitably supported at their ends, as by brackets 40 and 41, from the car frame. The sleeve 36 is held against 40 longitudinal movement in the bearings 37 by shoulders formed on said sleeve which engage the opposite faces of said bearings. The hub of the hand wheel 37 is formed with ratchet teeth 42 with which coöperates 45 a pawl 45 pivoted to the cross bar 39; said pawl normally locking said hand wheel against rotation and consequently serving to maintain the gate 31 in its normal position as shown in Fig. 3. By raising the pawl 45 50 the hand wheel 43 may be turned, thereby rotating the sleeve 36 which, being held against longitudinal movement in its bearings 37, causes the threaded stem 35 to be moved lengthwise to open or close the gate 31. 55 The end wall 21 of the car is provided with a suitable number (herein shown as three) of openings or poke holes 48 inclosed by frames 49 having upwardly directed extensions or hoods 50 provided at their upper 60 ends with horizontally disposed openings normally closed by covers or doors 51. By reason of the upwardly turned arrangement of the hoods 50 and the horizontal disposition of the openings therein the material in the car is prevented from escaping through

said openings when the covers 51 are opened, while access to the interior of the car, by means of a rod or other implement, is afforded through said openings.

The bottom slats 25 may, if desired, be of 70 a solid wooden or metallic construction as indicated in Fig. 4. Preferably, however, and as indicated at 250 in Figs. 8 and 9, said slats are of a suitable construction to constitute a filter which will allow any water in 75 the concentrates to be drained therefrom while standing in the car. As shown in said figures each slat 250 comprises a preferably 80 iron frame 251 having opposite rabbeted edges 260 corresponding to the rabbeted edges 26 of the form of slat shown in Fig. 4. The inner edges of the side and end members of the frame 250 are preferably rabbeted at both sides to receive the edges of thin metallic plates 252 formed with perforations 253 and secured together and to the frame 250 by means of bolts 254. Between the plates 252 and within the frame 251 is confined a quantity of a suitable filtering material 255, such as burlap, matting or 90 the like.

It will be seen that, with a car bottom composed of filtering slats such as those just described, any moisture in the concentrates standing in the car may be permitted to 95 drain off without, however, permitting the escape of the concentrates themselves.

The slats 250 may be of any suitable width. Preferably, however, said slats will be of a somewhat greater width than the width of 100 the solid slats when the latter are used in order to afford a maximum filtering area in proportion to the width of the slats.

The operation of unloading the car when filled with concentrates is as follows. The 105 pawl 45 is released from the ratchet teeth 42 and the hand wheel 43 turned to draw back or open the gate 31, as above explained, thereby leaving an opening in the car bottom between the endmost slat 25 or 250 and 110 the end wall 21 through which the concentrates previously supported by the gate 31 may fall. In order to assist in discharging this portion of the load the doors 51 may be opened and suitable implements inserted 115 through the poke holes 48 to dislodge the material at this end of the car. When this portion of the car has been sufficiently unloaded men with hoes may enter and draw down the concentrates through the opening 120 on an angle a little flatter than the natural angle of repose. As the slats are uncovered one by one they are moved in their guides 28, 29, toward the right or gate end of the car to take the place of the opening made by 125 withdrawing the gate 31, causing said opening to travel progressively the length of the car toward the left. In this way the concentrates may be hoed down on substantially their natural angle throughout the car and 130

discharged therefrom progressively from one end to the other thereof. When the car has been completely unloaded the slats, together with their supporting angle irons 28, 5 will be carefully swept off from the left end of the car and successively returned to their initial position until the right end of the car is reached, whereupon the gate 31 will be closed and locked by the pawl 45, thereby 10 tightly forcing the slats together, holding them in their normal position, and completely closing the bottom of the car ready to receive another load.

The material discharged from the car as 15 above described may, if desired, be received directly in a suitable bin located beneath the car. Preferably, however, said concentrates will be received upon a conveyer belt or the like and transported thereby to the usual 20 bedding bin where they are properly mixed with the other materials to make up a furnace charge. A suitable arrangement of apparatus for this purpose is shown in Fig. 1, wherein 52 denotes the rails or track upon 25 which the car runs, said rails being carried by stringers 53 supported by columns 54 above a receiving pit 55 in which is located a belt conveyer 56. 57 denotes a floor above the receiving pit 55 and having an opening 30 58 between the rails 52 and beneath which are arranged downwardly converging guide members 59 for directing the material discharged from the car upon the conveyer belt 56. The conveyer 56 is arranged longitudinally of the track and the opening 58 is of 35 a length at least equal to the length of the car, so that as said car is progressively unloaded from end to end, as above explained, the material discharged therefrom will all 40 be suitably received upon the conveyer 56 and transported thereby to the desired point.

While I have herein described my improved car with particular reference to its 45 use for the purpose of transporting and handling concentrates, it will be obvious that said car is by no means limited to such use, but that it might be employed to substantially equal advantage in connection 50 with other materials such, for example, as fine coal, sand, etc.

Having thus described my invention, I claim:

1. A car having a bottom composed of a 55 series of slats independently supported and guided for movement in a direction transverse to their length, and a gate for completing the series and adapted when closed to hold said slats in normal position to form 60 a continuous bottom.

2. A car having a bottom composed of a 65 series of slats independently supported and guided for movement in a direction transverse to their length, and a gate at the end 70 of the series for completing the same and

adapted when closed to hold said slats in normal position to form a continuous bottom.

3. A car having a bottom composed of a series of slats independently supported and 75 guided for movement in a direction transverse to their length, and a sliding gate at the end of the series for completing the same and movable longitudinally thereof, said gate when closed holding said slats in a predetermined position longitudinally of the 80 series to form a continuous bottom.

4. A car having a bottom composed of a series of slats independently supported and 85 guided for movement in a direction transverse to their length, a sliding gate at the end of the series for completing the same and movable longitudinally thereof, said gate when closed holding said slats in a predetermined position longitudinally of the 90 series to form a continuous bottom, and means to lock said gate in closed position.

5. A car having a bottom composed of a series of slats independently supported and 95 guided for movement in a direction longitudinally of said series and a gate for completing the series and adapted when closed to hold said slats in normal position to form a continuous bottom.

6. A car having a bottom composed of a 100 series of slats independently supported and guided for movement in a direction transverse to their length and a sliding gate at the end of the series for completing the same and movable longitudinally thereof, 105 said gate when closed holding said slats in a predetermined position longitudinally of the series to form a continuous bottom, said gate having a threaded shank, and a hand wheel coöperating with said shank to operate said gate.

7. A car having a bottom composed of a series of slats independently supported and 110 guided for movement in a direction transverse to their length and a sliding gate at the end of the series for completing the same and movable longitudinally thereof, 115 said gate when closed holding said slats in a predetermined position longitudinally of the series to form a continuous bottom, said gate having a threaded shank, a hand wheel coöperating with said shank for moving said gate and having a hub provided with ratchet teeth, and a pawl coöperating with said teeth to lock said gate in closed position.

8. A car having a bottom composed of 120 transversely extending slats arranged in a longitudinal series, means for supporting the ends of said slats and guiding the same for movement transversely of said slats and longitudinally of the series, and a gate for completing the series and adapted when closed to hold said slats in normal position to form a continuous bottom.

9. A car having a body provided with a 125

bottom composed of a series of slats independently supported and guided for movement in a direction longitudinally of the series, and a gate at the end of the series for completing the same, said body having an end wall adjacent said gate provided with one or more poke holes.

10. A car body having end walls, a bottom, and a gate in said bottom adjacent one of said end walls, said last named wall having one or more poke holes, upwardly disposed hoods inclosing said holes and having openings in their upper ends, and covers for closing said openings.

15. 11. A car having a body provided with downwardly converging lower side walls and a bottom composed of a series of separate slats and a gate for completing the series and adapted when closed to hold said 20 slats in normal position to form a continuous bottom.

12. A car having a body provided with downwardly converging lower side walls and a bottom composed of a series of slats 25 and a gate for completing the series and adapted when closed to hold said slats in normal position to form a continuous bottom, a frame for supporting said body having longitudinal girders to which said downwardly converging side walls are secured at their lower edges, and guides for the ends of said slats and for said gate carried by said girders.

13. A car having a bottom composed of a 35 series of slats having rabbeted edges forming shiplap joints, said slats being independently supported at their ends and guided for movement in a direction transverse to their length, and a gate for completing the series and having a rabbeted edge coöperating with the rabbeted edge of

the adjacent slat, said gate being adapted when closed to hold said slats in normal position to form a continuous bottom.

14. A car having a bottom composed of a 45 series of filtering slats independently supported and guided for movement in a direction transverse to their length, and a gate for completing the series and adapted when closed to hold said slats in normal position 50 to form a continuous filtering bottom.

15. A car having a bottom composed of a series of slats, each of said slats comprising a frame, a pair of foraminous plates located at opposite sides of said frame, bolts for securing said plates together and to said frame, and filtering material confined between said plates within said frame.

16. A car having a bottom composed of a series of slats, each of said slats comprising a frame having opposite rabbeted edges forming shiplap joints with the adjacent slats, foraminous plates located at opposite sides of said frame, bolts securing said plates together and to said frame, and filtering material confined between said plates within said frame, said slats being independently supported at their ends and being guided for movement in a direction transverse to their length, and a gate for completing the series and having a rabbeted edge co-operating with the rabbeted edge of the frame of the adjacent slat, said gate being adapted when closed to hold said slats in 70 normal position to form a continuous filtering bottom.

In testimony whereof I affix my signature, in presence of two witnesses.

ALEXANDER G. McGREGOR.
